UNITED STATES PATENT OFFICE

2,575,174

STATION INDICATOR

Benjamin B. Kirby, Kansas City, Mo.

Application June 16, 1947, Serial No. 754,791

4 Claims. (Cl. 40—42)

1

This invention relates to railway station indicators for mail cars, and has particular reference to a station indicator suitable for indicating to the mail clerk the approach of the train to a non-stop mail station.

On most railway systems where mail is carried provision is made for non-stop stations where mail is delivered and picked up mechanically. When these non-stop stations are being approached the mail to be delivered to that particular station must be thrown from the car so that it will land within a predetermined zone relative to the station. Furthermore, a pick-up hook is positioned on the train to take up the outgoing mail from the station. By means of this station indicator the mail clerk will be notified either audibly or visually of the train's approach to the railroad station so that he will have sufficient time to properly position the pick-up and delivery mechanism.

The principal object of the present invention is the provision of a station indicator that will automatically indicate the approach of a train to certain stations throughout its entire run or division.

Another object of this invention is the provision of a means for indicating non-stop stations by a means directly interconnected and driven by means operably driven by the car axle as it rotates.

A further object of the present invention is the provision of a station indicator including a film driving means operable to move said film in either of two directions across the face of the indicator.

Another object of the present invention is the provision of a film roll carrying indicia to designate non-stop stations along the railway route and means associated with said film and controlled thereby to indicate to the mail clerk the approach of the train to each of said non-stop stations.

Other objects are simplicity and economy of construction, ease of operation, and adaptability for use to indicate the approach of the train to any or all the railway stations along a given route.

With these objects in view, as well as other objects which will appear during the course of the specification, reference will now be had to the drawings wherein:

Figure 1 is a front elevation of a railway station indicator for mail cars showing diagrammatically its connection with the axle of a mail car, and embodying this invention.

Fig. 2 is an enlarged cross-sectional view taken

5 Fig. 3 is an enlarged front view of the station indicator with the front of the housing broken away and some of the parts omitted.

Fig. 4 is a horizontal sectional view taken on line IV—IV of Figure 3.

Fig. 5 is a reduced foreshortened sectional view taken on line V—V of Figure 2.

Fig. 6 is an enlarged sectional view of the drive gear.

10 Fig. 7 is an enlarged fragmentary view of the shifting mechanism with parts in section.

Fig. 8 is a fragmentary sectional view taken on line VIII—VIII of Fig. 7.

15 Fig. 9 is a diagrammatic view of the electric circuit.

Fig. 10 is an enlarged fragmentary sectional view taken on line X—X of Figure 1.

Throughout the several views of the drawings like reference characters refer to similar parts and the numeral 10 designates a housing or cabinet of elongated and substantially rectangular shape having a removable cover member 12 to facilitate adjustment and positioning of the parts within the cabinet. The front face of the cabinet is cut away at 14 to form an opening for the reception of a panel 16. This panel is elongated and fitted to extend a major length of the cabinet adjacent its central portion. An elongated central opening 18 is formed through panel 16.

20 Panel 16 is provided at its top and bottom marginal edges with vertically disposed flanges 20 spaced apart from the body of the panel to present grooves 22. These grooves are oppositely spaced to receive the marginal edges of a film 24.

25 Panel 16 is provided at its top and bottom marginal edges with vertically disposed flanges 20 spaced apart from the body of the panel to present grooves 22. These grooves are oppositely spaced to receive the marginal edges of a film 24 which is perforated at 26 along its marginal edges to receive the teeth 28 of driving rollers 30. These driving rollers 30 are alike in construction and are each provided with an axially disposed shaft 32 which extend outwardly from the ends of the

30 rollers for insertion in an upper bearing box 34 and a lower bearing block 36. These driving rollers are mounted respectively at opposite ends of cabinet 10 and are so positioned that they are in a common plane tangent to their outer peripheries, and this common plane coincides with the outer face of panel 16, so that film 24, when mounted for driving action on drive rollers 30,

35 will lie in grooves 22 to move over the face of panel 16. Intermediate the lower end of each of rollers 30 and the adjacent bearing block 36 is a beveled gear 38, which is fixed to shaft 32 and rotatable with the adjacent roller. A rod 40 disposed at right angles to shaft 32 with its axis intersecting the axis of said shaft, is mounted in

40 spaced relation above the bottom 42 of cabinet 10 with its opposite end portions fixed in bear-

45

55

ing blocks 36. A sleeve 44 is slidably mounted on rod 40 and is supported adjacent its central portion by spaced apart bearings 46. A worm gear 48 is positioned between bearings 46 and is mounted for rotation with sleeve 44 and is secured thereto by means of key 50 which allows for longitudinal movement of the sleeve relative to rod 40. Mounted on the right end of sleeve 44 is a beveled pinion 52 which is fixed to said sleeve and adapted to rotate therewith. Referring to Figure 5, it will be noted that pinion 52 is in mesh with one of the gears 38 for driving the adjacent roller 30. A beveled pinion 54 secured to the opposite end of sleeve 44 is spaced out of mesh with the adjacent gear 38 as shown. Means for shifting sleeve 44 along rod 40 comprises an operating lever 56 pivoted to a bracket 58 by means of pin 60. Lever 56 extends through an opening 62 formed through the front wall of cabinet 10 and is bifurcated at 64 and provided with radially disposed pins 66 which are adapted to engage in an annular groove 68 formed about the body of sleeve 70 which is affixed to sleeve 44 by means of set screw 72. The outer extremity of lever 56 extends through opening 62 and beyond the front face of cabinet 10 whereby it may serve as a hand grip for operating the shifting parts. It will be noted by referring to Figure 8 that lever 56 is recessed at 74 to receive a spring 76 and a ball 78 which form a resilient detent to engage in recesses 80 formed in the front wall of cabinet 10 for maintaining the lever arm in selected predetermined positions.

It will be noted that when the detent is in the position shown the drive pinion 52 will be intermeshed to drive the adjacent driving roller 30. When the detent is moved to the central position, neither of the pinions will be in mesh and the drive rollers 30 will be free to be moved in either direction. When the lever is moved so that detent 78 engages the right hand recess 80, pinion 54 will be in mesh with gear 38 to drive the other driving roller 30. It is quite apparent that pinion 52 will drive the tape in a right hand direction while the pinion 54 will drive the tape in a left hand direction, as viewed from the front of the cabinet.

The means for driving gear 48 and sleeve 44 is shown more or less diagrammatically and may consist of a gear 82 rigidly mounted on car axle 84 which carries a bearing plate 86 in which is carried a spur gear 88 disposed in mesh with gear 82. Affixed to axle 90 of gear 88 and rotatable therewith is a flexible drive member 92 which extends to coupling 94 by means of which it is rigidly attached to shaft 96 on which is fixed a worm drive 98. This shaft is mounted adjacent each end of worm 98 in a bearing block 100. Worm 98 is intermeshed with the driving gear or worm wheel 48 so that the driving of the drive rollers 30 is in a constant ratio to the travel of the car wheels on the track, thus it is possible to indicate as herein set forth, the exact position of the film tape 24 on the indicator as indicated by the position of the train along its route.

A take-up drum 102 rotatably mounted in cabinet 10 adjacent its right end is disposed with its axis of rotation in parallel relation with the axis of driving roller 30, and a take-up drum 104 is likewise mounted at the left end of the cabinet to take up the film fed off when the pinion 54 is in mesh and driving the feed roller 30. When pinion 52 is driving the film it will drive it in the direction indicated by the arrow

and the film will be drawn off of take-up drum 104 and will be wound on drum 102. In order to rotate the drums 102 and 104 in the proper direction for winding the film thereon, the following mechanism is provided: A tension spring 106 secured at its one end to the left end wall of cabinet 10 by means of a hook 108 is attached at its other end to a cable 110 which passes over a sheave wheel 112, rotatably mounted in a bracket 114 which in turn is secured to the right end wall of the cabinet. This cable is fixed to and passes about the axle 116 of drum 102 in a direction whereby when the film is delivered from the drive roller 30 as indicated by the arrows, spring 106 will contract and cause a rotation of drum 102 to wind the film thereon. Drum 104 is provided with a similar spring driving means including a tensioned spring 118 secured at its one end by a hook 120 secured to the right end wall of cabinet 10 and at its other end to a cable 122 which passes over a sheave wheel 124 mounted for rotation in a bracket 126 which in turn is secured to the left end wall of the cabinet.

It will be noted that when the film is being moved as indicated, the cable 122 will be wound about axle 128 of drum 102 thus energizing spring 118 so that when the end of the run has been reached and it is desired to reverse the direction of travel of the tape, the spring 118 will be fully energized to take up the film as it is fed to the left by the action of driving pinion 54.

Film 24 is made of an electrical insulating material and is utilized to normally maintain two switch members open as shown in one portion of the electric circuit shown in Figure 9.

Panel 16 is made of an electrical insulating material, and is provided adjacent its upper extremity with an opening 130 into which is fitted a spring contact member 132 secured at its one end by means of bolt 134 to panel 16. This member 132 normally rests against the inner face of film 24, however, film 24 is provided with an opening 136 to indicate certain non-stop stations and is adapted to register with the opening 130 as the film is moved lengthwise of the device and when these openings are in register the contact member 132 will move down to contact the stationary contact member 138 which is secured to the panel member 16. Adjacent the lower portion of film 24, panel 16 is provided with an opening 140. A spring contact member 142 is disposed with its one end in hole 140 to normally contact the inner face of film 24. This contact member is secured by means of bolt 144. A stationary contact member 146 is normally separated from contact 142 as suggested above; however, the film is also provided with a series of openings 148 which move in alignment with opening 140 and will register therewith as the film is driven, thus making it possible to close contact members 142 and 146 at predetermined positions of the film in its travel.

Indicia 150 are provided along the central transverse line of the film and are adapted to pass over the elongated slot or window 18 of the panel and be lighted by means of a suitable electric light 152 disposed in cabinet 10 adjacent window 18 so that the indicia will be readily visible to the mail clerk. It is the intention of the applicant to position these indicia so that they will be adjacent the central portion of the indicator as the indicated town is reached. For instance, as shown in Figure 3, 70 the film is being driven in the direction indi-

cated by the arrow and the non-stop town Roe is being approached, and as shown, the parts are in the position as shown in Figure 9, so that the signals will be operated as hereinafter described. This signal is usually given about a mile prior to the arrival at the station, therefore, when the station is reached the indicia Roe will have moved forwardly to substantially the center portion of the indicator, and the contact member 132 will have been raised and separated from the stationary contact point 138, thus opening the circuit so that the signaling device will be inactive. This same sequence will be followed as the various non-stop stations are approached.

Referring to the indicia Doe in Figure 3, it will be noted that its corresponding film opening 136 is disposed slightly in advance thereof. On the return trip when the film is moving in the opposite direction, that is, to the left, as indicated in Figure 3, the approach to the town will be from the opposite direction, therefore, it becomes necessary to provide the openings 148 which precede the adjacent indicia, thus making it possible to notify the mail clerk of the approach of the train to the non-stop station indicated. It is quite apparent that due to some irregularities in distances traveled beyond the station points at the end of the run, it might be necessary to readjust the starting point from the station and in order to accomplish this, the lever member 56 is adjusted to the central portion so that the operator may move the film to its correct position and then set the proper driving pinion in operative relation with the beveled gear 38 to drive the film and indicate the stations being approached in their proper sequences.

For convenience of setting the film, it will be noted that the shafts 32 are provided with squared extensions 154 which may be engaged by the crank arm 156 for rotating the proper drive roller for setting.

An audible signaling device such as an electric bell 158 and a visual signal 160 such as an electric light are provided to indicate the approach of the train to the railway station.

Referring to Figure 9, it will be noted that the battery 162 is connected at its one terminal through wire 164 to contact member 146 and also with contact member 138 through wire 166 which joins wire 164. The other terminal of battery 162 is connected by wire 168 to lamp 160, bell 158 and member 142. Wire 170 connects member 132 with wire 168 so that the signaling devices will be both operable whenever either the member 132 or 142 make contact with their respective contacts 138 or 146.

A wedge 172 slidably adjustable in housing 10 serves to be positioned between member 132 and panel 16 to prevent 132 from contacting member 138 when the film 24 is being moved to the left, also a wedge 174, best shown in Figure 10, is also slidably mounted in housing 10 to be moved to and from the position behind member 142 to control its contact with contact member 146.

What I claim as new and desire to protect by Letters Patent is:

1. A station indicating device for a vehicle comprising an apertured cabinet adapted to be mounted on said vehicle, a pair of spaced apart driving rollers carried rotatably in said cabinet, a roll of film of insulating material operatively associated with said driving rollers whereby said film is moved before the aperture of said cabinet, means for driving said rollers whereby the

speed of said film is synchronized with the speed of said vehicle, an electric alarm circuit including two pairs of terminal contacts connected in parallel, the contacts of each of said pairs being disposed respectively on opposite sides of said film and resiliently urged together, said film having a pair of apertures therein corresponding with each station indicated thereon and adapted by the movement of said film to be brought respectively between said pairs of contacts, thereby permitting engagement of said pairs of contacts, and means for selectively urging said pairs of contacts out of engagement with said film.

2. A station indicating device for a vehicle comprising an apertured cabinet adapted to be mounted on said vehicle, a pair of spaced apart driving rollers carried rotatably in said cabinet, a roll of film of insulating material operatively associated with said driving rollers whereby said film is moved before the aperture of said cabinet, means for driving said rollers whereby the speed of said film is synchronized with the speed of said vehicle, an electric alarm circuit including two pairs of terminal contacts connected in parallel, the contacts of each of said pairs being disposed respectively on opposite sides of said film and resiliently urged together, said film having a pair of apertures therein corresponding with each station indicated thereon, said pair of apertures being disposed respectively on opposite sides of said station indication longitudinally of said film and out of alignment transversely of said film, and adapted by the movement of said film to be brought respectively between said pairs of contacts, thereby permitting engagement of said pairs of contacts, and manually operable means for selectively urging said pairs of contacts out of engagement with said film.

3. A station indicating device for a vehicle comprising an apertured cabinet adapted to be mounted on said vehicle, a pair of spaced apart driving rollers carried rotatably in said cabinet, a roll of film of insulating material operatively associated with said driving rollers whereby said film is moved before the aperture of said cabinet, means for driving said rollers whereby the speed of said film is synchronized with the speed of said vehicle, an electric alarm circuit including two pairs of terminal contacts connected in parallel, the contacts of each of said pairs being disposed respectively on opposite sides of said film and resiliently urged together, said film having a pair of apertures therein corresponding with each station indicated thereon, said pair of apertures being disposed respectively on opposite sides of said station indication longitudinally of said film and out of alignment transversely of said film, and adapted by the movement of said film to be brought respectively between said pairs of contacts, thereby permitting engagement of said pairs of contacts, and a pair of wedges carried movably by said cabinet and manually operable to selectively urge one or the other of said pairs of contacts out of engagement with said film.

4. In a vehicle station indicator device of the class described including a film carried by said vehicle and means for driving said film in synchronism with the speed of said vehicle, an electric alarm circuit including two pairs of terminal contacts, the contacts of each of said pairs being disposed respectively on opposite sides of said film and resiliently urged against said film and normally held out of contact by said film, said film having stations indicated thereon and a pair

of apertures formed therethrough adjacent each station indication, said apertures being disposed on opposite sides of said station indication longitudinally of said film and respectively adjacent opposite edges of said film, said apertures being adapted by the movement of said film to be brought respectively between said two pairs of contacts to permit engagement of said pairs of contacts, means for reversing the travel of said film to correspond with the direction the vehicle travels over the route indicated on said film, and manual means for selectively urging one or the other of said pairs of contacts out of engagement with said film.
